UNITED STATES PATENT OFFICE.

GEORGE H. GILMAN, OF CLAREMONT, NEW HAMPSHIRE, ASSIGNOR TO SULLIVAN MACHINERY COMPANY, OF CLAREMONT, NEW HAMPSHIRE, A CORPORATION OF MASSACHUSETTS.

PNEUMATIC DRILL.

1,150,357.

Specification of Letters Patent. Patented Aug. 17, 1915.

Application filed May 28, 1914. Serial No. 841,615.

To all whom it may concern:

Be it known that I, GEORGE H. GILMAN, a citizen of the United States, and a resident of Claremont, New Hampshire, have 5 invented an Improvement in Pneumatic Drills, of which the following description, in connection with the accompanying drawings, is a specification, like characters on the drawings representing like parts.

10 This invention relates to rock drills and other tools, and among other objects provides a screw fed support for a hand tool having provision for detachable connection with the tool, so that the latter may be 15 positively fed by the screw of the support or may be operated independently thereof as desired.

The character of the invention will be best understood by reference to the following description when taken in connection with the accompanying drawings of one illustrative embodiment thereof, while its scope will be more particularly pointed out in the appended claims.

20 In the drawings: Figure 1 is a plan view of a hand drill and a support therefor illustrating one embodiment of the invention; Fig. 2 is a view in side elevation and partially in vertical section of the tool and support shown in Fig. 1; Fig. 3 is a plan view on a scale larger than shown in Figs. 1 and 2 of a cradle forming part of the support for the tool. Fig. 4 is a vertical longitudinal section through the cradle shown in Fig. 3; and Fig. 5 on an enlarged scale is a transverse section taken on line 5—5 of Fig. 2 with the tool removed.

25 Referring to the drawings and to the embodiment of my invention which I have selected for illustrative purposes, I have there shown a pressure fluid rock drill of the piston-hammer type comprising a cylinder 3 (Fig. 1) in which operates a usual piston constituting a hammer which delivers 30 a rapid succession of hammer blows upon the inner end of a drill bit 5. The latter is mounted in an elongated cylinder head 7 preferably supported in a yielding manner on the forward end of the cylinder 3 by means of a pair of tie rods 9, 9 and cushioning springs 11, 11. To arrest forward movement of the drill bit when struck by the piston hammer there is provided a tool retainer or stop 13 of any suitable construc-

tion. The tool is provided with a handle 15 55 formed to present an elongated eye 17 between said handle and the rear cylinder head 19.

At times the tool described is adapted to be held manually in operation and at other 60 times it may be desired to provide a support for the tool and feed the same positively relatively to the work by a feed screw. The support shown herein comprises a shell 21 having a trunnion 23 depending therefrom 65 and detachably connected to a usual clamp or saddle 25 shown herein as connected to a column 33, although obviously the trunnion may be connected to a tripod if desired.

Journalized in the shell 21 is a feed screw 70 35 adapted to be turned by a handle 37. The shell is provided with ways 39, 39 receiving slide flanges 41, 41 of the cradle. Depending from the cradle is an eye 43 receiving a nut 45 threaded to the feed screw 75 35. When the feed screw is turned by its handle the nut and cradle are caused to travel longitudinally thereof.

An important feature of the invention relates to the construction of the cradle whereby the tool may be readily detachably connected thereto. To accomplish this the cradle is provided with a head 47 projecting upwardly therefrom and formed to present a fixed jaw 49 to which a movable jaw 51 85 is hinged by a pin 53 extending through registering apertures in ears on said jaws. To lock the upper jaw in closed position there is provided a swing bolt 55 pivoted to the head 47 and received in an open slot in 90 the upper jaw, said bolt being held therein by a thumb nut 57. The head 47 is provided with inclined portions 59 against which the rear head 19 of the tool is adapted to rest, as more fully hereinafter described. The 95 cradle also is provided with a seat 60 curved to conform to the contour of the tool and having an incline 61 for engagement with a correspondingly inclined portion of the tool.

100 The tool is placed on the cradle with its handle resting in the lower jaw 49 and the upper jaw 51 entered through the handle eye 17, where it is held by tightening the swing bolt 55. The tool rests on the inclines 105 59 of the cradle and the incline 61 of the seat 60. One of the side rods 9 is received by a notch 63 in said seat. Since the tool

rests on the inclines 59 and 61 it tends to ride forwardly on its saddle and in so doing draws the handle tightly against the throat of the clamp jaws. The jaws are formed to conform to the contour of the handle aperture and thereby tightly grip a substantial extent of the handle and in so doing prevent any rotation of the body of the tool in the cradle and securely retain the same in the 10 cradle.

The head receiving the handle presents a strong, broad faced abutment against which rests the rear head of the cylinder and thereby resists any tendency to dislocate the tool 15 from its cradle by recoil. The inclined portion of the tool engaging the incline of the cradle seat is on the yieldingly supported end of the tool and acts through the springs and rods connecting said end to the rear 20 head of the cylinder to further contribute to the holding of the tool in its proper position. After the tool has been secured to its cradle it may be positively fed relatively to the work by turning the feed screw 35.

25 If it is desired to remove the tool and support and operate the same manually, it is simply necessary to release the single swing bolt and open the jaws. The tool is then free to be lifted from the cradle.

30 While the tool is shown herein within its handle in horizontal position, it will be understood that the cradle may support the tool with its handle in vertical position if desired.

35 Having described one illustrative embodiment of the invention without limiting the same thereto, what I claim as new and desire to secure by Letters Patent is:

1. In combination, a percussive tool having a body and a handle provided with an opening, a supporting cradle for the tool, said cradle being provided with a handle-supporting head comprising fixed and movable jaws, one of which enters the opening 45 in the handle, and means to hold said jaws in handle-engaging relation.

2. In combination, a percussive tool having a body and a handle provided with an opening, a supporting cradle for the tool, 50 said cradle being provided with a handle-receiving head comprising two jaws relatively movable with respect to each other, one of said jaws being adapted to enter said opening, and means to hold said jaws in handle-engaging relation.

3. In combination, a percussive tool having a body and a handle provided with an opening, a supporting cradle for the tool, said cradle having a member to support said 55 handle in a position transversely of the cradle, and a coöperating member adapted to pass through the opening of said handle and to coöperate with said handle support-

ing means in maintaining said handle in position. 65

4. In combination, a percussive tool having a body and a handle provided with an opening, a supporting cradle for said tool, said cradle having two members pivoted together and adapted to receive said handle 70 between them, one of said members passing through the opening.

5. In combination, a percussive tool having a body and a handle provided with an opening, a supporting cradle for the 75 tool, said cradle having a member to support said handle in a position transversely of the cradle, a coöperating member adapted to pass through the opening of said handle and to coöperate with said handle support- 80 ing means in maintaining said handle in position, and coöperating means to support the body of the tool.

6. In combination, a percussive tool having a body and a handle provided with an 85 opening, a supporting cradle for said tool, said cradle having two members pivoted together and adapted to receive a handle between them, one of said members passing through the opening, and coöperating means 90 to support the body of the tool.

7. In combination, a percussive tool having a body and a handle, a supporting cradle having handle and body supports for the tool, one at least of said supports having 95 a forwardly extending incline to receive the tool.

8. In combination, a percussive tool having a body and a handle, a supporting cradle having handle and body supports for the tool, each of said supports having a forwardly extending incline to receive the tool, and one of said supports having means to clamp the tool thereto.

9. In combination, a percussive tool having a body and a handle 105 provided with an opening 17, a supporting cradle for said tool having a tool supporting head 47 provided with a handle receiving seat and a co- 110 operating jaw 51.

10. In combination, a percussive tool having a body and a handle 15 provided with an opening 17, a supporting cradle for said tool having a tool supporting head 47 provided with a handle receiving seat and a co- 115 operating jaw 51, said jaw 51 being adapted to pass through opening 17, and means for maintaining said jaw and said supporting head in handle-engaging relation.

In testimony whereof, I have signed my 120 name to this specification, in the presence of two subscribing witnesses.

GEORGE H. GILMAN.
